UNITED STATES PATENT OFFICE.

GEORGE W. BEATTY, OF DECATUR, ILLINOIS.

FIRE-CONTROL APPARATUS.

Application filed July 1, 1926. Serial No. 119,960.

(GRANTED UNDER THE ACT OF MARCH 3, 1883; 22 STAT. L. 625.)

The invention described herein may be used by the Government, or any of its officers or employees in prosecution of work for the Government, or by any other person in the United States, without payment to me of any royalty thereon, in accordance with the Act of March 3, 1883.

The present invention relates to fire control apparatus and more especially it has reference to means for entering a percentage correction into fuse ranges.

In determining the fuse range to be given a projectile certain corrections to allow for conditions of the atmosphere, the gun and the ammunition must be included. Where the target is stationary or moving at a slow speed a flat correction suffices for the purpose but in the cases of rapidly moving aerial targets the fuse range varies with each shot and within wide limits. When an approaching plane comes within range of the gun the fuse range is approximately three times greater than when the plane at the same altitude arrives overhead. Consequently, since planes remain in range only a short interval it is desirable to produce a large volume of fire and obviously there is not time to introduce a different flat correction into each fuse setting.

The principal object of the present invention therefore is to provide means for introducing a percentage correction into the fuse range.

With these and other objects in view which will appear as the description proceeds, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a view in side elevation of an apparatus embodying the principles of the invention;

Fig. 2 is a plan view thereof;

Fig. 3 is a sectional view on the line 3—3 of Fig. 4;

Fig. 4 is a sectional view on the line 4—4 of Fig. 2;

Fig. 5 is a sectional view on the line 5—5 of Fig. 1;

Fig. 6 is a sectional view on the line 6—6 of Fig. 3;

Fig. 7 is a side view of a fuse for which the particular apparatus shown is designed;

Fig. 8 is a view in side elevation of the cam adjusting member;

Fig. 9 is a sectional view on the line 9—9 of Fig. 8; and

Fig. 10 is a sectional view on the line 10—10 of Fig. 8.

Referring to the drawings by numerals of reference:

The invention as shown is embodied in a fuse setting machine of the type which is provided with two relatively rotatable adjusting members, a crank for independently rotating the member is coupled to the time ring of the fuse and a worm gear for rotating the other member which is coupled to a fixed part of the fuse. The adjustment of the fuse is effected by causing the time ring adjusting member to carry out two complete revolutions while the other member is either stationary or may be under continuous operation. Inasmuch as a fuse setting machine of this character is described in detail in a copending application, Serial No. 98,286, and since it forms but one method of obtaining a member which is rotatable proportionate to the principal uncorrected fuse range it will be only briefly described.

Referring to Figs. 1 and 3 the fuse setting machine is mounted on a base 5 and comprises a housing 6 in which two adjusting members 7 and 8 are independently rotatable about the axis of the machine. The member 7 is adapted to be coupled to the adjustable part of the fuse, namely, the rotatable time ring 9, (see Fig. 7) by means of a lever 7^a and lugs 9^a, while the member 8 is adapted to be coupled to the fixed part of the fuse, for example, the base 10, by means of a lever 8^a and lugs 10^a.

In order that the fuse setting machine may be capable of engaging and setting the fuse irrespective of the position of the lugs with relation to each other or to the machine, the adjusting member 7 is directly connected to a crank 11 for rotating said member until its lever 7^a picks up the lug 9^a on the time ring and places it in a predetermined position while at the same time a

rotational movement will be imparted to the round until the fixed lug 10^a on the base of the fuse snaps into engagement with the levers of the adjusting member 8. In order to insure that the round will be rotated sufficiently for the fixed lug to pick up the levers on the member 8 it is necessary to move the crank through two complete revolutions.

- 10 A worm 12 serves for imparting to the adjusting member 8 and the fixed lug 10^a of the round an angular position relative to the predetermined position of the time ring 9 which corresponds to the uncorrected fuse 15 range. The member 8 is inscribed with a range scale 13 readable against an index 14 whose normal angular position establishes the predetermined position to which the rotatable time ring 9 is moved. The index is 20 on a movable ring 15 which is mounted on the member 8 and is retained against an end plate 16 by a cover plate 17. The index is thus movable from its normal position and as will presently appear is used to introduce corrections into the fuse range.

The adjusting member 8 (see Fig. 8) is formed centrally with a circular portion indicated by the line 18 so that when a follower 19 is resting thereon it will partake 30 of no vertical movement and this position of the follower corresponds to zero correction. On either side of the line 18 the periphery of the member 8 constitutes a cam surface which varies according to the angular position of the member 8 as represented 35 by the range scale and whose origin indicated by the line 20 corresponds to zero on the range scale. The periphery of the member 8 along the line 20 coincident with zero 40 range will thereafter be parallel to the axis of said member and no movement is imparted to the follower under these conditions irrespective of its position with respect to the line 18.

45 The portion 21 of the cam surface at the right of the line 18 elevates the follower and adds the correction to the members and the portion 22 at the opposite side lowers the follower and deducts the correction. 50 The follower (see Figs. 3 and 4) is yielding mounted in a carriage 23 which is movable longitudinally of the apparatus by means of a screw shaft 24 to position the follower with respect to the zero line 18 an 55 amount corresponding to the desired percentage correction, plus or minus, which is readable on the correction scale 25. The vertical movement of the follower is converted into rotary movement of a shaft 26 through the intermediation of a segmental gear 27 and the shaft is connected by segment gear 28 to the movable ring 15 so that it displaces the index 14.

The direction of movement of the shaft 60 65 26 is dependent on the engagement of the

follower with the increasing cam 21 or the decreasing cam 22 while the degree of its movement is dependent on the distance of the follower from the zero correction represented by the line 18 and also by its distance from the origin of the cam represented by zero range or the line 20. The cam thus automatically applies the percentage correction as read on the scale 25 to any particular fuse range and the rotation of 70 the shaft 26 which controls the displacement of the index 14 is proportional to the percentage correction.

The apparatus is also designed for a method of operation wherein it is to be 75 used in conjunction with a system of synchronous transmission of data. According to this method a pointer 29 movable proportionate to the uncorrected fuse range is under continuous control from the battery 80 commander's station and a second pointer 30 controlled by the movement of the adjusting member 8 of the fuse setting machine is maintained in coincidence therewith. The movement of the shaft 26 which is proportionate to the percentage correction is 85 therefore combined with the movement of the adjusting member 8 which is proportionate to the principal or uncorrected fuse range and this is accomplished by interposing a differential gearing 31 into which the movements of these members are respectively introduced by gears 26^a and 8^b of proper ratio.

I claim:

1. A fuse setting machine embodying an adjusting member rotatable proportionate to uncorrected fuse range and provided with a range scale, the periphery of said member forming an increasing and decreasing cam surface varying according to the range scale, a carriage movable longitudinally of the member amounts corresponding to percentage corrections, a cam follower mounted in the carriage, a member controlled by the movement of the follower and rotatable proportionate to the percentage correction and a ring movable with the correction member and bearing an index against which the range scale is read.

2. A fuse setting machine embodying an adjusting member rotatable proportionate to uncorrected fuse range and provided with a range scale, the periphery of said member forming an increasing and decreasing cam surface varying according to the range scale, a carriage movable longitudinally of the member, amounts corresponding to percentage corrections, a cam follower mounted in the carriage, a member controlled by the movement of the follower and rotatable proportionate to the percentage correction and a differential gearing for combining the movements of the range and correction members.

3. Fire control apparatus embodying a cam member rotatable proportionate to uncorrected fuse range, a cam follower movable longitudinally of said member in measurable amounts corresponding to percentage corrections, a second member actuated by the follower and rotatable proportionate to the percentage corrections, means for comparing the individual movements of the range and percentage correction members and means for combining their movements.
4. A fire control apparatus embodying a cam member rotatable proportionate to uncorrected fuse range, a cam follower movable measurable amounts corresponding to percentage corrections, a second member actuated by the follower and rotatable proportionate to the percentage corrections, means for comparing the individual movements of the range and percentage correction members and means for combining their movement.
5. Fire control apparatus embodying a cam member rotatable proportionate to uncorrected fuse range, a cam follower movable measurable amounts corresponding to percentage corrections, a second member actuated by the follower and rotatable proportionate to the percentage corrections, and means for comparing the individual movements of the range and percentage correction members.
6. Fire control apparatus embodying a cam member rotatable proportionate to uncorrected fuse range, a cam follower movable measurable amounts corresponding to percentage corrections, a second member actuated by the follower and rotatable proportionate to the percentage corrections, and means for comparing the individual movements of the range and percentage correction members.
7. Fire control apparatus embodying a member rotatable proportionate to uncorrected fuse range, a second member rotatable proportionate to the percentage correction to be included in the fuse range, and means movable longitudinally of the range member and in constant engagement therewith whereby the movement of the correction member is controlled by the range member.
8. Fire control apparatus embodying a member rotatable proportionate to uncorrected fuse range, a second member controlled by the first member and positionable therewith to be rotated proportionate to the percent correction of a given range and means for representing the total corrected range.
9. Fire control apparatus embodying a member rotatable proportionate to uncorrected fuse range, a second member controlled by the first member and positionable therewith to be rotated proportionate to the present correction of a given range.
10. Fire control apparatus embodying a member movable proportionate to uncorrected fuse range, a second member movable proportionate to the percentage correction of the range represented in the movement of the first member and means for representing the total corrected range.

GEORGE W. BEATTY.

Certificate of Correction.

It is hereby certified that in Letters Patent No. 1,612,851, granted January 4, 1927, upon the application of George W. Beatty, of Decatur, Illinois, for an improvement in "Fire-Control Apparatus," an error appears in the printed specification requiring correction as follows: Page 3, line 65, claim 9, for the word "present" read *percent*; and that the said Letters Patent should be read with this correction therein that the same may conform to the record of the case in the Patent Office.

Signed and sealed this 1st day of February, A. D. 1927.

[SEAL.]

M. J. MOORE,
Acting Commissioner of Patents.
